UNITED STATES PATENT OFFICE.

HARRISON J. CAMP, OF NEW BERLIN, NEW YORK.

BRAKE-SHOE.

1,110,744.

Specification of Letters Patent. Patented Sept. 15, 1914.

Application filed March 10, 1914. Serial No. 823,748.

To all whom it may concern:

Be it known that I, HARRISON J. CAMP, a citizen of the United States, residing at New Berlin, in the county of Chenango and State 5 of New York, have invented certain new and useful Improvements in Brake-Shoes, of which the following is a specification.

This invention relates to improvements in brake shoes for rolling stock.

10 The object of the invention is to improve the construction of brake shoes for rolling stock, particularly locomotives, and to provide an extremely simple and inexpensive brake shoe having fastening means adapted 15 to hold the brake shoe on a brake head until the said shoe is entirely worn out.

A further object of the invention is to provide a brake shoe having fastening means adapted to effectively prevent the brake 20 shoe from falling off the brake head and becoming lost, and capable of enabling the said shoe to be instantly removed from the brake head and again easily and quickly replaced thereon.

25 The above and additional objects are accomplished by such means as are illustrated in their preferred embodiment in the accompanying drawings, described in the following specification and then more particularly pointed out in the claims which are appended hereto and form a part of this 30 application.

In describing my invention in detail reference will be had to the accompanying drawings wherein like characters denote like or 35 corresponding parts throughout the several views, and in which Figure 1 is a perspective view of an assembled brake shoe illustrating the application of the invention; 40 Fig. 2 is a similar view of the said shoe, the constituent parts thereof being separately shown; and Fig. 3 is an inverted end view.

Before proceeding with the description of the drawings, I desire to call particular 45 attention to the fact that while I have evolved my invention with reference to its application in connection with rolling stock, particularly locomotives, the same may be readily utilized as a brake shoe for wagons, 50 carriage, and other vehicles varying in type.

Referring now to the drawings by numerals, 1 designates, as an entirety, the head

portion of the shoe, said head being provided with a central opening 2 for the reception of the brake beam (not shown). 55 Said head 1 is grooved as indicated at 3, the groove extending entirely around the head and longitudinally thereof at a point adjacent that face of the head against which the brake shoe proper designated as an entirety 60 by the numeral 4 abuts. The said face of the head 1 is centrally recessed as at 5 to provide for the reception of an enlargement 6 of the shoe 4 to tightly engage, when the shoe is assembled, shoulders, designated respectively 7 and 8 formed at the respective ends of the said recess. Said shoe 4 is also grooved as indicated at 9, said grooves likewise extending longitudinally of the shoe in spaced relation to and adjacent the inner 70 or head engaging face of said shoe. Shoulders 10 and 11 are formed at the respective ends of the enlargement 6, said shoulder 10 being adapted for engagement with the shoulder 8 of the head, and the shoulder 11 75 being adapted for engagement with the shoulder 7 of the head, which engagement, the said shoe and head being properly assembled, will lock the one against longitudinal movement independent of the other. 80 The opposite face of the shoe 4 from that abutting the head 1 is arcuately formed as indicated at 12 for an obvious purpose.

Attached, as indicated at 13 to the head portion 1 of the shoe is a retaining plate 14, 85 the respective ends of which are upturned as at 15 to fit the respective grooves 3 and 9 of the head and shoe. One of the said upturned ends 15 is at all times within the groove 3, while the other of the said ends 90 15, upon the separation of the shoe from the head, is withdrawn from engagement with the said groove 9. The shoe and head being assembled, a fastening member, designated as an entirety by the numeral 16 is arranged 95 thereover to maintain the said shoe and head in rigid relation, said fastening member being substantially U-shaped in form, the respective extensions thereof as well as the connecting portion, being provided with 100 longitudinal flanges, one upon each of the respective longitudinal edges thereof. Said flanges, as indicated in Figs. 1 and 2 of the drawings, fit the grooves 3 and 9 to in this

manner lock the shoe and head as desired. As a means whereby the fastening member 16 is maintained with its several flanges within the grooves 3 and 9, a retaining pin 5 17 of the cotter type, is provided, said pin being insertable through openings 18 of the fastening member and through a groove 19 extending transversely of the shoe 4 and in registration or alinement with the said 10 openings 18. To facilitate removal of the fastening member 16, a ring 20, or other like element, is attached thereto.

When it is desired that the several elements comprising the shoe, be separated or 15 disassembled, the pin 17 is first removed, and the fastening member withdrawn from engagement with the head and shoe. The removal of the said fastening member will allow the said head and shoe to fall apart, 20 that is, will allow the enlargement 6 of the shoe to be withdrawn from the recess 5 of the head, the engagement between one of the upturned ends 15 and the shoe serving as a fulcrum during separating operation. Said 25 shoe having been separated to this extent by disengaging the shoulder 10 and the shoulder 8, the former, that is the shoe 4, may be longitudinally moved to entirely separate or disengage the same from the head. 30 A reverse operation to that just described, will provide for the rearrangement of the several component parts.

From the foregoing, taken in connection with the accompanying drawings, it is apparent that the shoe 4 may be removed, readily and quickly replaced, by the withdrawal of the fastening member 16 from engagement with the shoe; that either the head or the shoe 4 may be removed, renewed, 40 and replaced, the two being made separate for that particular purpose; and that to provide for the separation of the said head and shoe, the shoulders 8 and 10 are slightly beveled as indicated in the said Fig. 2 of the drawings.

In reduction to practice, I have found that the form of my invention, illustrated in the drawings and referred to in the above description, as the preferred embodiment, 50 is the most efficient and practical; yet realizing that the conditions concurrent with the adoption of my device will necessarily vary, I desire to emphasize the fact that various minor changes in details of construction, 55 proportion and arrangement of parts may be resorted to, when required, without sacrificing any of the advantages of my invention, as defined in the appended claims.

Having thus fully described my invention, 60 what I claim as new and desire to secure by Letters Patent, is—

1. A brake shoe including a stationary and a removable shoe section, a detachable fastening member arranged to straddle the respective sections and to engage the said sec-

tions throughout their entire length, and means holding the fastening member immovable relatively to the respective sections, as and for the purpose set forth.

2. A brake shoe including a stationary 70 and a removable shoe section, each of the said sections being longitudinally grooved, a fastening member arranged to straddle the respective sections, the said member being adapted to fit the respective grooves to hold 75 the said sections immovable relatively to each other, and means holding the fastening member in place, as and for the purpose set forth.

3. In a separable brake shoe, a head portion having a groove extending longitudinally thereof, a shoe portion having a groove extending longitudinally thereof, and a fastening member having flanges fitting the respective grooves for maintaining the said 85 two portions rigid one with the other, as and for the purpose set forth.

4. In a separable brake shoe, a head portion, a shoe portion, the said head portion having a recess formed therein, an enlargement formed upon said shoe portion, said enlargement fitting said recess to lock the said two portions against longitudinal movement, one independent of the other, and a fastening member adapted for engagement 95 with the said head and shoe for locking same against movement in any direction other than longitudinal, as and for the purpose set forth.

5. In a separable brake shoe, a head portion having a longitudinal groove formed therein, a shoe portion having a longitudinal groove formed therein, the said head portion and shoe portion being engageable one with the other, the engaging surface of the 100 said head portion having a recess formed therein, an enlargement upon said shoe portion fitting said recess, the engagement between the said enlargement and the walls of the said recess preventing longitudinal 110 movement of either the head or shoe independent of the other, and a fastening member having flanges adapted for engagement with the respective grooves aforesaid for locking the said head and shoe against movement in any direction other than longitudinal, as and for the purpose set forth.

6. In a separable brake shoe, a head portion having a groove extending entirely therearound and longitudinally thereof, a shoe portion having a groove formed therein to extend entirely therearound and longitudinally thereof, said head portion having a recess formed therein, an enlargement 120 upon said shoe portion fitting said recess, the said enlargement preventing longitudinal movement of either the head or shoe independent of the other, a retaining plate rigid with the said head, the respective extremities 125 of the said plate being upturned to fit the 130

respective grooves aforesaid, a substantially U-shaped fastening member, flanges formed upon the respective longitudinal edges of the extensions of the fastening member and 5 also the connecting portion thereof, said flanges fitting the grooves of the said head and shoe to maintain the same incapable of movement other than longitudinal and in-

dependent of each other, as and for the purpose set forth.

In testimony whereof I affix my signature in presence of two witnesses.

HARRISON J. CAMP.
